UNITED STATES PATENT OFFICE.

JOHN F. O'CONNOR, OF CHICAGO, ILLINOIS, ASSIGNOR TO WILLIAM H. MINER, OF CHICAGO, ILLINOIS.

RAILWAY DRAFT-RIGGING.

1,120,231.

Specification of Letters Patent.

Patented Dec. 8, 1914.

Application filed March 9, 1914. Serial No. 823,275.

To all whom it may concern:

Be it known that I, JOHN F. O'CONNOR, a citizen of the United States, residing at Chicago, in the county of Cook and State 5 of Illinois, have invented a certain new and useful Improvement in Railway Draft-Rigging, of which the following is a full, clear, concise, and exact description, reference being had to the accompanying drawings, 10 forming a part of this specification.

My invention relates to improvements in draft rigging for railway cars.

The object of my invention is to provide a draft rigging of durable and efficient construction.

In the drawings forming part of this specification, Figure 1 is a plan view of a draft rigging embodying my invention; Fig. 2 is a side elevation partly in vertical longitudinal section on line 2--2 of Fig. 1, showing the parts in normal position; Fig. 3 is a cross-section on line 3--3 of Fig. 1; Fig. 4 is a side elevation partly in vertical longitudinal section, showing the position of 25 the parts in full buff; Fig. 5 is a side elevation partly in vertical longitudinal section illustrating a modification.

Referring to the drawings, the numerals 6--6 indicate draft sills or parts of the car-frame to which the draft rigging is applied; 30 7 a draw-bar, the rear end thereof only being shown in the drawings, and having a transverse key slot 8.

The numeral 9 indicates sills depending 35 from the draft sill 6 and forming a part of the draft members, the said members 9 being preferably secured to the members 6 by means of the angle-irons 10, which are suitably secured to the depending member 9, 40 preferably by the rivets 11--11, and to the sill 6 by the bolts 12--12. Mounted between the sills, and preferably secured to the upper portions of the members 9--9 by the rivets 13--13, is a spring case 14 provided at either side with the forward riveting flanges 15--15 and the rearwardly extended flanges 16--16. The spring case 14 contains the downwardly opening spring chamber 17, the said chamber being formed preferably 45 by the continuous plate 18, having a horizontal portion 19 forming the upper end of the chamber, dependent portions 20--20 forming the front and rear ends of the chamber, the said portions of the plate 18 50 being turned outwardly and upwardly at

their ends, as indicated at the numerals 21--21 in Fig. 2 of the drawings, to give this part sufficient strength. A spring member 22, comprising preferably a series of flat spring plates 23--23, are secured within the chamber 17 by means of a bolt 24 passing through the front and rear walls 20--20 of the chamber and through the perforations 25--25 through the upper portions of the plates 23--23. The front and rear walls 60 of the chamber 17 are slightly divergent from the upper portion of the chamber to permit a limited forward and rearward flexing movement of the springs therein. At their lower ends the springs enter a recess 65 26 in the upper face of a friction block 27, the friction block having a lower bearing face 28 and inner front bearing face 29 and inner rear bearing face 30. The bearing faces 29 and 30 form the front and rear 70 walls, respectively, of the chamber 26 in the friction block, and are suitably divergent from the lower end of the chamber 26 to permit a flexing of the spring member 22, and a sliding engagement between the 75 springs and the rear inner bearing face 30 on forward movement of the friction block, and between said springs and the inner forward bearing face 29 on rearward movement of the friction block.

The friction block 27 is inclosed within a yoke 50 horizontally disposed and having at its forward ends the slots 51--51 for the passage of the coupler key 52 therethrough and through the registering slot 8 in the 90 draw-bar, and in preferable construction through suitable slots in the adjacent portions of the draft members. The lower bearing face 28 of the friction block 27 bears against the bottom portion 31 of the channel 32 longitudinally formed in the supporting member 33, which is suitably secured between the draft members, preferably by means of bolts 34--34 passing through the members 9 of the draft members and through 100 perforated dependent flanges 35--35 with which the supporting member is provided.

On rearward movement of the draw-bar, the friction block 27 is forced rearwardly, the springs 22 resisting the rearward movement of the block and being flexed rearwardly thereby, meanwhile having at their forward face a frictional engagement against the forward inner bearing face 29 of the friction block 27 until the said springs en- 110

gage the inner forward bearing face 29 along its entire length and are in the position illustrated in Fig. 4 of the drawings.

- On forward movement of the draw-bar, 5 the springs are flexed forwardly by the forwardly moving friction block, the action between the springs and the rear inner bearing face of the friction block 30 being similar to the action just described in reference 10 to the bearing face 29 on rearward movement of the draw-bar. In both forward and rearward movement of the draw-bar, the tendency of the friction block to move downward by reason of the engagement of the 15 springs against the one or the other of the inner bearing faces 29 and 30 results in further frictional action between the supporting plate 23 and the lower bearing face 28 of the friction block 27.
- 20 In the modification illustrated by Fig. 5 of the drawings, the numeral 53 represents draft sills, each with a depending draft member 54 secured thereto, a spring case 55 secured between the draft members and having 25 the downwardly opening spring chamber 56 with the flat springs 57 depending therefrom, the upper ends of the said springs being secured within the chamber 56 by the bolt 58 passing through the front and 30 rear walls 59 and 60, respectively, forming said chamber, the said walls being suitably outwardly divergent toward the opening of the chamber, the lower ends of the springs 57 entering a chamber 61 of the friction 35 block 62. The front wall 63 of the chamber 61 and the rear wall 64 of the chamber 61 are convex in form to permit a frictional engagement between the said walls and the springs 57 on forward and rearward movement of the 40 friction block 62. The friction block 62 has a lower bearing face 72 engaging against the supporting plate 65, which is suitably secured between the draft members by the bolts 66-66. The friction block 62 is inclosed 45 within the horizontal yoke 67, said yoke being keyed to the draw-bar 68 by the transverse key 69 passing through suitable slots 70 in the yoke and draw-bar. A stop 71 is 50 secured between the draft sills rearwardly to the friction block 62 to limit the rearward movement thereof in buffing action of the gear. In the modified form, on forward movement of the draw-bar the springs 57 are flexed forwardly, and on rearward movement 55 are flexed rearwardly. In both movements of the draw-bar the springs are in frictional engagement with portions of the front and rear walls 63 and 64 of the friction block 62, and the lower bearing face of 60 the friction block is in frictional engagement with the supporting plate 65.

I claim:

1. In a draft rigging for railway cars, the combination with draft members, draw-bar and draft yoke, of a spring case secured be-

tween the draft members, a friction block, a supporting member and springs, the springs being mounted in the spring case at one end, and engaging the friction block at the other end, and having frictional engagement with 70 said block upon movement thereof.

2. In a draft rigging for railway cars, the combination with draft members, draw-bar and yoke, of a friction block and a bearing member for said block, and flat springs, the 75 springs being in engagement at one end with the friction block, and at the other end having rigid connection with the draft member.

3. In a draft rigging for railway cars, the combination with draft members, draw-bar and yoke, of springs, a mounting for said springs secured to the draft members, a friction block disposed below said mounting, a bearing face supporting said block, the springs being in engagement with the 80 friction block and adapted to be flexed by the movements thereof.

4. In a draft rigging for railway cars, the combination with draft members, draw-bar and draft yoke, of a supporting member secured between the draft members, a longitudinally reciprocating friction block engaging the supporting member, flat springs and a mounting therefor between the draft members, the said flat springs engaging the friction block and being adapted to resist both 90 forward and rearward movements thereof.

5. In a draft rigging for railway cars, the combination with draft members, a draw-bar and yoke, of a friction block, a supporting member therefor, and springs, the 100 springs being secured to the draft members and engaging the friction block at their free. ends.

6. In a draft rigging for railway cars, the combination with draft members, a draw-bar and yoke, of flat springs, a supporting member and a friction block, the friction block being provided with a chamber to receive the lower ends of the springs, the 105 upper ends of the springs being secured between the draft members.

7. In a draft rigging for railway cars, the combination with draft members, a draw-bar and draft yoke, of a supporting plate, 115 a friction block, a spring case and springs, the spring case being mounted between the draft members, the springs being dependent from the spring case and engaging the friction block at the lower ends, the friction 120 block being provided with front and rear inner friction faces for engagement with the springs on longitudinal movement of the friction block.

8. In a draft rigging for railway cars, the 125 combination with draft members, draw-bar and yoke, of a friction block, a supporting plate therefor, a spring case, flat springs secured thereto and dependent therefrom, the friction block being provided with front and 130

5 rear inner friction faces for engagement with the springs on movement of the friction block, the friction block bearing against the supporting plate on forward and rear-
ward movement of the draw-bar.

9. In a draft rigging for railway cars, the combination with draft members, draw-bar and yoke, of a spring case secured to the draft members, spring plates secured to the
10 spring case and depending therefrom, a friction block and a supporting member, the friction block having front and rear inner friction faces and an outer lower friction face, the springs engaging the friction block
15 between the front and rear inner friction faces and having frictional engagement with one of said faces on forward movement of the draw-bar, and with the other of said faces on rearward movement of the draw-
20 bar.

10. In a draft rigging for railway cars, the combination with draft members, draw-
bar and draft yoke, of a spring case having front and rear lateral flanges secured to the

25 draft members, a spring chamber in said case, springs entering said chamber, secured therein and depending therefrom, a friction block and a supporting member therefor, the friction block having front and rear inner friction faces between which the
30 springs are disposed, the said springs resisting the rearward and forward movements of the friction block through spring pressure and frictional engagement with said block.

11. In a draft rigging for railway cars, 35 the combination with draft members of a draw-bar and yoke, springs secured at their upper ends between the draft members, a friction block and means for supporting the same, the free ends of the springs engaging 40 the friction block and affording both spring and frictional resistance to the longitudinal movements of said block.

JOHN F. O'CONNOR.
